UNITED STATES PATENT OFFICE.

AQUILA B. MARSHALL, OF NEW YORK, N. Y., ASSIGNOR TO THE BOYNTON FURNACE COMPANY, OF NEW YORK.

STEAM OR HOT-WATER HEATER.

SPECIFICATION forming part of Letters Patent No. 600,267, dated March 8, 1898.

Application filed November 12, 1897. Serial No. 658,247. (No model.)

To all whom it may concern:

Be it known that I, AQUILA B. MARSHALL, of New York, in the county and State of New York, have invented certain new and useful 5 Improvements in Steam or Water Heaters, of which the following is a full, clear, and exact description.

My invention relates to improvements in heaters; and the objects of my invention are 10 to produce a comparatively simple heater which is adapted to heat water for direct circulation or to convert it into steam, which is constructed so as to be very easily set up or taken down, which has an extremely large 15 heating-surface, to the end that much of the heat of combustion can be utilized for heating water, and which is constructed and arranged so as to have a circulation within itself and thus avoid to a great extent the 20 difficulty in many heaters which have a tendency to force the water from the heater into the circulation-pipes.

To these ends my invention consists of a heater the construction and arrangement 25 of which will be hereinafter described and claimed.

Reference is to be had to the accompanying drawings, forming a part of this specification, in which similar figures of reference indicate 30 corresponding parts in all the views.

Figure 1 is a vertical section of my improved heater on the line 1 1 of Fig. 2. Fig. 2 is a sectional plan on the line 2 2 of Fig. 1, and Fig. 3 is a sectional plan on the line 3 3 35 of Fig. 1.

The heater has substantially the usual form of base 10, on which rests the bottom section 11 of the heater, this section being preferably 40 of a generally cylindrical shape, although it will of course be understood that the heater may be given any preferred cross-sectional shape without affecting the invention. This lower section 11 has an inner chamber 12, forming the fire-pot, and which has the usual 45 or any preferred form of grate. The section 11, like the other sections to be referred to presently, is hollow-walled, so that the water may surround the fire-pot, and it is pierced with the usual door-opening 13 and has at 50 the back a portion of the smoke-flue 14, be-

tween which and the fire-pot is a deflector 15, formed like the wall of the fire-pot and the smoke-flue, this wall being hollow to provide for the circulation of water, and as it inclines forward it has a tendency to throw forward 55 the products of combustion, which pass up through the flues in the sections above, which will be hereinafter referred to.

Above and resting on the section 11 are superposed sections 16 and 17, the body of the 60 heater being formed of these sections 11, 16, and 17; but it will of course be seen at once that any necessary number of sections can be used, this depending on the size and capacity of the heater. The sections 16 and 17 are 65 provided with deflecting-plates 16^a and 17^a, which extend transversely across the water-holding portions of the said sections and occupy the front portion thereof, the deflecting- 70 plates being lowest at the front edges and inclining upward toward the rear, so as to assist the circulation of water, as indicated by the arrows in Fig. 1 and as pointed out more specifically hereinafter.

The water-holding portions of the sections 75 16 and 17 do not connect at the rear, but connect at the front only through the nipples 19, and also connect through said nipples with the lower section 11 and with the dome 20, which is also hollow-walled to contain water. 80 It will be seen by reference to Fig. 1 that this makes a connection between the several sections of the boiler at the front only; but other circulatory devices can be substituted for the nipples shown, if preferred.

The dome 20 is preferably of the usual 85 rounding shape and rests on the section 17, the dome comprising an outer hollow ring 22, from which rises the water-legs 23, these uniting at the center to connect with the out-flow-pipe 26. The bottom of the smoke-chamber connects with the fire-pot 12 by the flues 21, which are preferably vertical and parallel and which pierce the sections 16 and 17, any necessary number of these flues being made. 90 The sections 16 and 17 are also pierced by the vertical smoke-flue 18, which connects with the flue 14 above referred to, and the flues 14 and 18 form a continuous flue leading from the dome 20 to the smoke-pipe 25; but, if de- 95 100

sired, a direct connection between the dome and smoke-pipe can be made, as shown by dotted lines at 25^a in Fig. 1.

The rear portion of the dome 20 connects by 5 an outside water-leg 24 with the lower back part of the section 11, so that the only rear connection between the upper and lower water-holding sections of the heater is through this leg 24. Consequently it will be seen at once 10 that the outside air will have a tendency to cool the leg, so that the water will be a few degrees cooler here than in the interior portions of the cylinder, and the cooler water will therefore descend through the leg 24 15 and pass into the section 11, from which, being heated around the fire-pot, it will rise through the lower nipple 19, through the section 16, being deflected by the plate 16^a toward the back of the said section, then flow 20 forward above the deflecting-plate, as shown by the arrow in Fig. 1, thence up through the second nipple 19 to the section 17, thence back upon the deflecting-plate 17^a, thence 25 forward again to the upper nipple 19, thence through the ring 22 and water-legs 23 of the dome 20, and thence back through the water-leg 24, thus keeping up the constant inner movement. The outflow is through the pipe 26 and the return is through the pipe 27, connecting with the lower part of the section 11.

From the foregoing description it will be seen that this heater is very simple, that the sections going to make it up can be laid one on the other with great ease, that an immense heating-surface is provided, thus affording economical heating of the water, and that a good means of inner circulation is provided.

Having thus described my invention, I claim as new and desire to secure by Letters 40 Patent—

1. An improved heater, comprising a lower hollow-walled section containing a fire-pot, superposed water-holding sections above said lower section, the said sections being connected with each other and with the lower section at one side only of the heater, and an exterior water-leg connecting the upper and lower sections at the opposite side of the heater, substantially as described.

50 2. An improved heater, comprising a lower water-holding section containing a fire-pot with a forwardly-deflecting inclined water-holding wall at the back of the fire-pot, su-

perposed water-holding sections mounted on the lower section and provided with smoke-flues, suitable connections between the said sections, and a smoke-flue to carry off the products of combustion, substantially as described.

3. An improved heater, comprising a lower 60 water-holding section containing a fire-pot, superposed water-holding sections pierced with smoke-flues and mounted on the lower section, interior connections between the front portions of the several sections, an 65 exterior connection between the upper and lower sections only, and interior deflecting-plates in the said water-holding sections whereby the water is given a tortuous course through them, substantially as described. 70

4. In a heater, the combination of the upper and lower water-holding sections independently connected, of the intermediate water-holding sections connected together and with the upper and lower sections to provide 75 water circulation, and deflecting-plates in said intermediate sections arranged opposite the connections between the sections, substantially as described.

5. A heater of the kind described, comprising a lower water-holding section having a fire-pot, a rear smoke-flue and an inclined deflecting hollow wall between the smoke-flue and fire-pot, superposed water-holding sections on the lower section, said sections having 85 smoke-flues adapted to connect with the fire-pot and with the first-mentioned smoke-flue, a water-dome on the said sections, water connections between the said sections and the water-dome, interior deflecting-plates arranged within the intermediate sections and opposite the water connections, and an exterior connection between the water-dome and the lower section, substantially as described. 90

6. A heater, comprising a series of superposed independent water-holding sections having suitable connections for circulation and for draft, means for heating the water, connections within the sections between all the said sections, and an exterior connection 100 between the upper and lower sections, substantially as described.
